UNITED STATES PATENT OFFICE.

JACOB FELBEL, OF NEW YORK, N. Y., ASSIGNOR TO UNION TYPEWRITER COMPANY, OF NEW YORK, NEW YORK, A CORPORATION OF NEW YORK.

TYPE-WRITING MACHINE.

No. 890,037. *Specification of Letters Patent.* Patented June 9, 1908.

Application filed November 21, 1906. Serial No. 344,455.

To all whom it may concern:

Be it known that I, JACOB FELBEL, citizen of the United States, and resident of the borough of Manhattan, city of New York, in the county of New York and State of New York, have invented certain new and useful Improvements in Type-Writing Machines, of which the following is a specification.

My invention has to do with the ribbon mechanism of typewriting machines and more especially of that class of machines in which the ribbon is usually normally removed from the printing point and is caused to cover the printing point to coöperate with the printing instrumentalities when the latter are actuated.

In my pending application filed March 6th, 1905, Serial No. 248,569, I show a ribbon normally removed from the printing point and divided into two longitudinal fields substantially equal in width, and provide means for giving said ribbon a constant throw so that during printing operations it is moved to and fro or vibrated to cover the printing point. The means just referred to comprises a vibratory ribbon carrier of the usual construction found in the Monarch typewriting machine to which the invention disclosed in said pending application is shown as applied, although of course any other suitable vibratory carrier may be used, and the constant throw imparted to said carrier causes only one of the longitudinal fields or stripes to be brought opposite the printing point and made use of. When it is desired to employ the other field or stripe of the ribbon, the ribbon carrier is moved by hand and latched or held fixed in such a position that said other ribbon field is brought opposite the printing point. At this time, it will be understood, no vibratory movement is imparted to the ribbon carrier during printing operations and said ribbon carrier acts in effect as a stationary ribbon guide. Of course when the first used field is again to be employed the ribbon carrier is unlatched and once more brought under the control of the vibrating mechanism so that it may be moved to and fro to bring the first ribbon field opposite the printing point during printing operations. The longitudinal stripes or fields into which the ribbon shown in said application is divided are different in character, the difference commonly being one of color. One of the colors is usually black or

blue and the other is usually red. In the ordinary run of work the black or blue field of the ribbon is used a great deal more than is the red field and consequently when the black or blue field is worn out or exhausted and the ribbon is discarded the red or little used field will still be comparatively fresh. In other words, the ribbon has to be discarded although only about half of it is worn out. This undesirable feature is, of course, found in other ribbon mechanisms in which narrow polychrome ribbons are used in two lines, one lengthwise of each color-field or in which the paths of the type impressions on the two color-fields correspond. To reduce this defect to a minimum and to more uniformly exhaust a ribbon having a plurality of longitudinal colored fields, or stripes of different characteristics, is one of the main objects of my present invention.

Further objects will hereinafter appear.

To the above ends my invention consists in the features of construction, combinations of devices and arrangements of parts herein-after described and particularly pointed out in the claims.

One way of carrying out my improvements is shown in the accompanying drawings, wherein my invention is shown as applied to the Monarch typewriter and embodied in a mechanism having the general characteristics of my hereinbefore referred to application; that is to say, the ribbon carrier is given a vibratory movement when one ribbon field is to be employed and is held fixed or stationary like a mere ribbon guide when another ribbon field is to be employed.

In carrying out my invention in the present instance, however, I make use of a ribbon somewhat wider than the usual ribbon employed on the Monarch and other visible writing machines and divide said ribbon into two longitudinal fields or stripes having different characteristics or colors. One field, preferably the black field, is of a width substantially equal to the ordinary ribbon and the other field, preferably the red field, is quite narrow, being wide enough to receive only a single line of type impressions. The ribbon is controlled by a ribbon carrier which has a single normal position but which is adapted to be thrown or moved variable distances under the influence of the printing keys so as to bring different widthwise portions of the wider field of the ribbon opposite

the printing point. The means shown for variably actuating the ribbon carrier is substantially the same as that employed in the Monarch machine and when this variable actuating means is operative the type impressions are caused to follow in a wavy or serpentine path extending from side to side of the wider ribbon field and longitudinally thereof. I further provide means for rendering the variable actuating means inoperative on the vibrator at will and for raising the vibrator and latching or holding it stationary in such a position that the narrow ribbon field is brought opposite the printing point, the result being that the type impressions are caused to follow in a substantially straight path longitudinal of the narrow ribbon field.

The features and advantages of my invention will be clearly understood from the following specification considered in connection with the accompanying drawings, wherein

Figure 1 is a vertical longitudinal sectional view, taken about centrally, of a typewriting machine embodying my invention. Fig. 2 is a fragmentary sectional view corresponding with Fig. 1 but showing parts of the ribbon vibrating devices in different relations from those in which they appear in said Fig. 1. Fig. 3 is a transverse vertical sectional view of the machine taken on a plane represented by the line $x-x$ in Fig. 1 and looking in the direction of the arrows at said line. Fig. 4 is an enlarged fragmentary perspective view showing parts of the ribbon vibrating devices and parts of my improvements associated therewith as they appear when viewed from above at the front and somewhat to the left of the middle of the machine. Fig. 5 is a fragmentary rear elevation, partly in section, and showing parts of the ribbon vibrating mechanism as they appear when disconnected from the ribbon operating lever.

In the drawings, the main frame of the machine is shown as comprising a base 1, corner posts 2 and a top plate 3. Key levers 4 are fulcrumed on a plate 5 in the rear of the base, each key lever being provided with a restoring spring 6 and having pivoted to it at 7 a sub-lever 8. The lower end portion of each sub-lever is slotted at 9 to coöperate with a fixed abutment 10 and the upper end of each sub-lever is connected by a link 11 with a type bar 12 pivotally mounted in a hanger 13, said hanger being secured by a headed screw 14 to a vertically arranged segmental type bar support 15. The hangers 13 are arranged in segmental series and the free ends of the type bars are normally supported on a segmental type rest 16, being adapted to coöperate, when the associate type bar actuating mechanism is operated, with the front face of a rotary platen 17 mounted in a platen carrier comprising side bars 18 (only one of which is shown) joined at the rear by a rear 65 or slide bar 19. The top and bottom faces

of the slide bar 19 are grooved to coöperate with anti-friction balls 20, the latter also co-operating with grooved top and bottom guide rails 21 secured by screws 22 to standards 23 fixed to and rising from the top plate. 70 A feed rack 24 is mounted on the platen carrier and normally meshes with a feed pinion 25 which is operatively connected with a toothed escapement wheel 26. Coöoperating with the latter are escapement dogs 27 75 mounted at the top of a pivoted vibratory dog carrier or rocker 28, said rocker having a horizontally disposed arm 29 connected by a link 30 with an arm 31 fixed to and extending rearwardly from a rock shaft 32 pivoted on screw pivots 33 fixed in the sides of the base 1. The arm 31 and rock shaft 32 are part of a universal bar frame, the latter also comprising side arms 34 and a universal bar proper 35 extending from side to side of the machine beneath the key levers 4 and fixed to the side arms 34 and central arm 31. A spring drum 36 is connected by a band or strap 37 with the platen carrier and constantly tends to draw the latter leftward over 90 the top plate. When any of the key levers 4, or the spacing levers (not shown), are actuated the universal bar 35 is operated and the escapement devices are caused to coöperate in a known manner to permit the carriage to 95 be drawn a letter space distance toward the left by the spring drum 36.

Ribbon spools 38 are mounted above the top plate, one at each side of the machine and forwardly of the platen. A ribbon 39 is 100 wound upon said spools and has its ends secured thereto, said ribbon passing from one spool to the other in front of the platens. The ribbon shown in the drawings is somewhat wider than the ribbon commonly employed on the Monarch typewriter and is divided into two longitudinal printing fields or stripes *a* and *b*, the field *a* being preferably of a width substantially equal to the usual Monarch ribbon, and the field *b* being considerably narrower and wide enough preferably for only a single line of type impressions. The fields *a* and *b* as shown are different in character; the field *a*, for example, may be of one color such as black and the field *b* of a different color such as red, or the field *a* may be copying ribbon and the field *b* record ribbon. Any suitable ribbon feeding mechanism may be employed to alternately rotate the ribbon spools and wind the ribbon back and forth between them. The ribbon feeding mechanism shown in the drawings resembles that used in the Monarch machine and will be briefly described. Each ribbon spool 38 is mounted at the upper end of a vertical shaft 40, fixed to the lower end portion whereof is a small beveled gear 41. Meshing with each gear 41 is a beveled pinion 42 at the forward end of a horizontally disposed shaft 43, the latter carrying at its 110 115 120 125 130

rear end a beveled pinion 44 which is adapted to mesh with a beveled driving pinion 45 fixed to a horizontally disposed driving or power shaft 46. The latter is operatively connected with the spring drum so as to receive rotary motion therefrom when said spring drum is turned in one direction by means comprising two beveled pinions 47 and 48, the beveled pinion 47 being connected with the spring drum by the usual pawl and ratchet mechanism (not shown) and the beveled pinion 48 being connected by the usual pin and slot connection 49, 50 with the driving shaft 46, the construction being such that while the driving shaft may be moved back and forth endwise without affecting the beveled pinion 48, yet said shaft and pinion will always rotate together. It will be understood that each ribbon spool is provided with a gear train like that above described and that there are two driving pinions 45, one at each end of the driving shaft 46, said driving pinions being adapted to engage alternately with their associate pinions 44 when the driving shaft is given endwise motion to and fro by the usual or other suitable means.

Midway between the ribbon spools the ribbon is threaded through a vibratory ribbon carrier or vibrator 51 which is or may be of a style employed in some Monarch machines, but which has ribbon receiving slots 52 which are somewhat longer than heretofore in order to accommodate the slightly wider ribbon 39. The ribbon carrier 51 is guided and supported on the upright arms 53 of a guide bracket 54 which is secured by screws 55 to the top plate of the machine. The lower end of the stem of the ribbon carrier is slotted and the slot is bridged by a cross pin 56 which cooperates with a slot 57 in the forward end of a ribbon operating lever 58, the latter being pivoted at 59 in a lug 60 depending from the under side of the top plate. The rear arm of the lever 58 is formed with an elongated slot 61 which receives a pin or stud 62 fixed to and projecting laterally from the upper end of an actuating link 63 which is pivotally connected at 64 with the arm 31 of the universal bar frame. Extending forwardly and downwardly from the upper end portion of the link 63 below the stud 62 is an arm 65, the lower portion whereof is parallel with the upper part of the link 63, thus providing a strap which cooperates with an eccentric member 66, the latter having a reduced collar portion 67 which receives a set screw 68 for securing the eccentric member in a fixed relation with the driving shaft 46. The working face of the eccentric 66 is broad enough to enable the driving shaft 46 to be shifted endwise without disconnecting the eccentric member from its strap. It will be understood that when the key levers are actuated and the universal

bar 35 is depressed, the link 63 will be drawn downwardly, and, because of the pin and slot connection 61, 62 with the ribbon operating lever 58, will swing the forward arm of said lever upwardly raising the ribbon carrier 51, 70 and bringing the ribbon carried thereby opposite the printing point where it will cooperate with the actuated type bar. It will further be understood that during the movements of the carriage in letter space direction 75 the driving shaft 46 will be rotated, thereby causing the eccentric member 66 to rotate, said eccentric member co-operating with its strap to swing the link 63 on its pivot 64 and to vary the position of the stud 62 in the slot 61, said stud being automatically moved back and forth towards and away from the fulcrum 59 of the operating lever. By this means the throw of the operating lever is varied and the widthwise portion of the ribbon which is presented to the types will also be automatically varied so that the type impressions will follow in a path which as it proceeds lengthwise of the ribbon curves or waves from side to side thereof. The ribbon actuating mechanism as thus far described does not differ essentially from the corresponding mechanism of the Monarch machine, but in the latter the wavy path followed by the type impressions extends practically from one edge of the ribbon to the other, while in my present construction although the proportions and arrangements of the ribbon actuating mechanism is substantially the same, yet, owing to the additional width of the ribbon employed, the wavy path of the type impressions will be limited to the field *a* of the ribbon 39 and will extend from one edge to the other of said field *a* without at any time encroaching upon the ribbon field *b*.

In order to make use of the ribbon field *b* means are provided for disconnecting the actuating link from the ribbon operating lever and thereafter raising said lever by hand-operated devices and maintaining said lever fixed in a position where the ribbon field *b* may be opposite the printing point. After the actuating link has been disconnected, and prior to the raising of the ribbon operating lever by said hand-operated devices, the ribbon will remain down in normal position if the printing keys be actuated. Accordingly, if it is desired to dispense with the ribbon entirely, the hand-actuated means 115 for raising the operating lever need not be used. This feature will be more clearly understood from what follows. Referring first to the disconnecting means, the actuating link 63 is provided with an extension 63^a 125 extending upwardly from the top part of the link above the stud 62. As clearly shown in Fig. 4 the extension 63^a is received in and guided by a slot 69 formed in the end portion 70 of a plate-like disconnecting member or

slide 71 which is arranged to slide back and forth against the under side of the top plate of the machine and is guided and supported by headed screws 72 which pass through slots 73 formed in said slide and engage in threaded openings in the top plate. The slot 69 is open at one end to facilitate assembling and extends lengthwise of the operating lever 58 and of the slot 61 therein, said slot 69 being of such length that during the automatic to and fro movements of the stud 62 in the slot 61 the extension 63^a will at all times be contained in the slot 69 and consequently the link 63 will always be under the control of the disconnecting member or slide 71. As shown in the drawings the plate-like slide 71 lies against the under side of the top plate at the right of the operating lever 58, said slide being confined between the top plate and the heads of the screws 72. Between the slot 69 and the left-hand one of the two slots 73 the slide 71 is formed with a rectangular opening 74 which is bridged by a cross pin 75. Adapted to coöperate with the cross pin is a cam slot 76 and a dwell 77 formed in a segmental arm 78 of a camming member, the latter also comprising a vertical arm 79 from which the arm 78 curves forwardly and downwardly. The lower end of the arm 79 terminates in a collar portion 80 which is perforated to receive a rock shaft 81 to which said collar is fixed, the camming member being thereby secured to the inner end of the rock shaft in a fixed relation with the latter, and being adapted to extend or pro-trude upwardly through an opening 3^a cut in the top plate 3. The rock shaft 81 extends laterally towards the left of the machine as shown in Fig. 3 and is journaled in a lug 82 depending from the under side of the top plate and in the flange 3^b of the top plate at the left-hand side thereof. The outer end of the shaft 81 projects through the flange and has suitably fixed to it a finger piece or handle 83 by which the rock shaft and the devices carried thereby may be conveniently adjusted or set by the operator. The means shown in the drawings (see Fig. 3), for securing the finger piece to the rock shaft comprises a pin 83^a which is driven through a collar portion 83^b of said finger piece, which collar portion fits over the end of said rock shaft, the inner face of said collar portion abutting against the flange 3^b of the top plate and serving to prevent endwise motion of the rock shaft in one direction.

It will be understood that when the rock shaft and the camming member containing the slot 76 are in the positions illustrated in Figs. 1 and 4, the slide 71 will be disconnected from said camming member and the actuating link 63 will be operative on the vibrator lever 58. When, however, the handle or finger piece 83 is pulled forwardly the rock shaft is turned and the cam slot 76

brought into engagement with the cross pin 75, forcing said cross pin, and through it the slide 71, rightward until the end of the cam slot 76 is reached and the dwell 77 enters into engagement with the cross pin 75. During this forward turning movement of the camming member, the segmental portion 78 will pass downwardly through the rectangular opening 74 in the slide 71. As the latter is moved or slid toward the right the inner wall of the slot 69 will engage with the extension 63^a and pull it towards the right, withdrawing the stud 62 from the slot 61 and causing the link 63 to swing laterally or transversely of the operating lever 58 and about the pivot 64 as a center. The link 63 is pivotally secured to the arm 31 of the universal bar frame in such a way that there is sufficient yield or give in the connection to permit a lateral swinging movement of the link 63 in the manner just described. When the camming action of the slot 76 on the cross pin 75 ceases, the link 63 will have been moved to the position shown in Fig. 5, wherein it will be noted that the stud 62 has been entirely withdrawn from the slot in the operating lever 58 and that said lever and its actuating link are entirely disconnected. It will further be seen from an inspection of this figure that the working face of the eccentric member 66 is so broad that even in disconnected position the link 63 will still be in engagement with said eccentric member.

If it is desired to dispense altogether with the use of the ribbon, as is sometimes the case, (for example, when mimeographing is to be done) the forward turning of the rock shaft may be discontinued when the upper end of the cam slot 76 has been reached by the cross pin 75. As has been stated, when this occurs the link 63 will have been disconnected as shown in Fig. 5. It will be apparent that when the parts are in the relations shown in this figure, if the printing keys be operated the link 63 will be vibrated without affecting the ribbon operating lever, and the latter, together with the ribbon carrier 51 and the working portion of the ribbon, will remain inoperative in normal position.

In order to raise the ribbon carrier and maintain it in a fixed position, thereby rendering the field b of the ribbon operative, I preferably employ a finger or projection 84 having a collar portion 85 through which the rock shaft 81 passes and which is fixed to said rock shaft in position to abut the left-hand face of the lug or bearing 82. The finger is adapted to be turned when the rock shaft 81 is turned or rocked and to be thereby brought into coöperative engagement with the top of the rear arm of the operating lever 58. When the actuating link 63 is in engagement with the operating lever, however, the finger stands in the position shown

in Figs. 1 and 4, the rounded end 84^a of the finger, which is its contactive or engaging part, being at this time raised some distance from the operating lever but lying directly over the rear arm thereof. Preferably, a washer 86 is arranged on the stud 62 at the right of the operating lever 58 and suitably secured in place so that normally, or when the link 63 is operative, its extension 63^a will be some distance to the right of the finger 84 and the left arm of the end portion 70 of the slide 71 will not come directly beneath the finger 84. Consequently the path of the latter or the space between it and the top of the rear arm of the operating lever 58 will normally be open and unobstructed. The finger is so arranged with relation to the operating lever 58 and the camming member containing the slot 76 that as the rock shaft 81 is turned to render the cam slot 76 operative on the cross pin 75, the rounded contact end 84^a of the finger will approach the rear arm of the operating lever but will not engage it. As soon, however, as the end of the cam slot 76 reaches the cross pin 75 and the dwell slot 77 begins to embrace said cross pin, the finger will contact with the operating lever and as the turning movement of the rock shaft 81 is continued said finger will depress the rear arm of said operating lever until at the end of the forward turning of the rock shaft the operating lever will have been brought to the position illustrated in Fig. 2. The forward turning movement of the rock shaft is limited by a pin or stop 87 extending from the rock shaft near the handle and adapted to contact with the under side of the top plate (Fig. 2). The reverse motion of the rock shaft may be limited by the rear wall of the slot 3^a in the top plate against which the back of the camming member may strike. The finger is so arranged with respect to the operating lever that when it is prevented from further moving the lever by the stop pin 87, said finger will act as a latch to hold the operating lever in the position to which it has been raised. This will be understood from a consideration of Fig. 2. It will furthermore be seen from an inspection of this figure that the operating lever has been raised so far and latched or held fixed in such a position that the ribbon carrier and ribbon have been moved further upward than they are at any time by the actuating link 63 during printing operations, and that the lower field *b* of the ribbon is opposite the printing point in position to coöperate with the printing instrumentalities when they are actuated. It will be understood that as the actuating link is at this time inoperative on the lever 58, the operation of the printing instrumentalities and consequent depression of the universal bar and actuating link will not affect the ribbon carrier and ribbon. In other words, the ribbon carrier will at this

time act as a fixed guide and the ribbon will be fed past the printing point in a straight line so that the type impressions along the field *b* will follow a straight path longitudinal of said field *b*. 70

During the operation of the cam slot 76 on the cross pin 75 and the consequent movement of the slide 71, the rock shaft 81 will be held from leftward endwise movement and the camming member will be caused to turn 75 or rotate in a fixed path by reason of the engagement of the left-hand face of the collar portion 85 of the finger with the right-hand face of the lug 82 supporting said rock shaft. As has been said, the collar portion 83^b of the 80 finger piece 83 coöperates with the flange 3^b of the top plate to prevent endwise movement of the rock shaft in the opposite direction. Consequently, it will be seen that while said rock shaft may be turned or rotated freely, 85 it is held from moving endwise in either direction and the camming and shifting devices thereon, the latter comprising the finger 84, will be confined to fixed paths of rotation. During the time that the cam slot 90 76 is operative and the stud 62 is being withdrawn from the slot 61 the finger 84 will be inoperative, and during the time that the finger 84 is in operation the dwell 77 will be embracing the cross pin 75 and the slide 72 95 will remain motionless in the position to which it has been moved by the cam slot 76, said position being illustrated in Fig. 5.

When it may be desired to again render the ribbon field *a* operative the operations above 100 described are reversed, the handle 83 being pushed rearwardly, causing a rearward movement of the rock shaft 81 and restoring the devices carried thereby to the first positions, or those illustrated in Figs. 1, 3 and 4 of the 105 drawings. It will be understood that as the finger 84 is turned backwardly it will permit the rear arm of the operating lever 58 to rise to normal position, the weight of the forward arm of said lever combined with the weights of the 110 vibratory ribbon carrier and that portion of the ribbon between the spools being sufficient to effect this restoring movement of the operating lever. But if desired a light spring might be added to assist the lever 58 back to 115 normal position and promptly. As soon as the contact end 84^a of the finger separates from the operating lever the top end of the cam slot 76 will begin to act on the cross pin 75 and during the further backward turning 120 movements of the rock shaft 81, the cam slot 76 acts to cam back the slide 71 to the position first described and to cause a reengagement of the stud 62 with the slot 61 in the operating lever. 125

From what has been said it will be seen that by my improvements there may be used a ribbon having one field of substantially the same width as the ordinary narrow ribbon employed in visible writing machines and 130

having also a comparatively narrow additional field; that the invention is especially adapted to the employment of a ribbon in which the wide ribbon field differs in color or kind of ink from the narrow ribbon field; that ordinarily the wider field will be operative and will be utilized both lengthwise and crosswise, so that the ink with which said field is impregnated will be thoroughly exhausted and will give as much service, or enable as much printing to be done, as is the case with the usual narrower ribbon having the same width as the single field *a*; that as the narrower field, when the color of the fields differ, is seldom used, it will last usually as long as the wider field which though it has more inking surface is used more often than the narrower field; that by a simple hand operation the use of the ribbon may be entirely dispensed with; that this hand operation effects a relative displacement between certain of the parts constituting the connections between the ribbon carrier and the finger keys for operating the printing instrumentalities; that by a continuance of said operation the narrower ribbon field may be rendered operative so that an entire change in the character of the writing may be had than when the first or wider ribbon field is in use; and that by said continuance of said operation the shifting member or finger is brought into cooperation with a part of the connections between the ribbon carrier and the printing keys, said part in the present instance being the ribbon operating lever.

Various changes may be made within the scope of my invention and the appended claims.

What I claim as new and desire to secure by Letters Patent, is:—

1. In a typewriting machine, the combination with a ribbon having a plurality of printing fields, of means for automatically vibrating the ribbon so as to move different widthwise portions of one of the printing fields to and from the printing point at printing operation; hand-actuated means operative to render said vibrating means inoperative at will; and hand-actuated means operative at will to position the ribbon with another of its printing fields at the printing point.

2. In a typewriting machine, the combination with a ribbon having a plurality of printing fields, of a ribbon carrier; finger keys; connections between said finger keys and said ribbon carrier, which connections are operative to move the ribbon carrier when the finger keys are actuated so as to bring different widthwise portions of one of said ribbon fields into use; means for displacing one portion of said connections relatively to another so that actuation of the finger keys will be inoperative to transmit motion to the ribbon carrier; and means op-

erative to set said ribbon carrier to bring another printing field of said ribbon into use.

3. In a typewriting machine, the combination with a ribbon having a plurality of printing fields; of a vibratory ribbon carrier; actuating means therefor comprising a link and a lever normally connected together; automatic means for varying the point of connection between said link and lever to vary the throw of the ribbon carrier and use the ribbon widthwise in one of said fields; means for disconnecting said link and said lever at will; and means for moving said ribbon carrier at will so as to bring another of said fields of the ribbon opposite the printing point.

4. In a typewriting machine, the combination with a ribbon having a plurality of printing fields; of a vibratory ribbon carrier; actuating means therefor comprising a link and a lever normally connected together; automatic means for varying the point of connection between said link and lever to vary the throw of the ribbon carrier and use the ribbon widthwise in one of said fields; means for disconnecting said link and said lever at will, said means comprising a slideable member, a camming member operative thereon, a finger piece, and connections between said finger piece and said camming member, and means for moving said ribbon carrier at will so as to bring another of said fields of the ribbon opposite the printing point.

5. In a typewriting machine, the combination with a ribbon having a plurality of printing fields; of a vibratory ribbon carrier; actuating means therefor comprising a link and a lever normally connected together; automatic means for varying the point of connection between said link and lever to vary the throw of the ribbon carrier and use the ribbon widthwise in one of said fields; means for disconnecting said link from said lever at will; and means for moving said ribbon carrier at will so as to bring another of said fields of the ribbon opposite the printing point, said last named means comprising a shifting member or finger operative on said lever, a finger piece, and connections between said finger and said finger piece.

6. In a typewriting machine, the combination with a ribbon having a plurality of printing fields; of a vibratory ribbon carrier; actuating means therefor comprising a link and a lever normally connected together; automatic means for varying the point of connection between said link and lever to vary the throw of the ribbon carrier and use the ribbon widthwise in one of said fields; means for disconnecting said link from said lever at will, said means comprising a slideable member, a camming member operative thereon, a finger piece, and connections between said finger piece and said camming

member; and means for moving said ribbon carrier at will to bring another of said fields of the ribbon to the printing point, said last named means comprising a finger operative 5 on said lever to shift the same and maintain it in shifted position.

7. In a typewriting machine, the combination with an inking ribbon having a plurality of printing fields; of a vibratory ribbon 10 carrier; actuating means therefor comprising a link and a lever normally connected together; automatic means for varying the point of connection between said link and lever to vary the throw of the ribbon carrier 15 and use the ribbon widthwise in one of said fields; means for disconnecting said link from said lever at will, said means comprising a slide connected with said link, and devices consisting of a camming member, a rock 20 shaft, and a finger piece for actuating said slide at will; and means for moving said ribbon carrier at will so as to bring another of said fields of the ribbon to the printing point.

8. In a typewriting machine, the combination of a ribbon carrier; means for actuating the same comprising a link and a lever normally connected together; and devices operative at will to disconnect said link and lever and to set said ribbon carrier opposite 25 the printing point, said devices comprising a hand-actuated rock shaft, and a camming member and shifting member both fixed on said rock shaft.

9. In a typewriting machine, the combination of a ribbon carrier; means for actuating the same comprising a link and a lever normally connected together; devices operative at will to disconnect said link and lever and to set said ribbon carrier opposite the printing point, said devices comprising a hand-actuated rock shaft, a finger fixed thereon 30 and operative on said lever to shift the same and a camming member also fixed thereon; and a slide constantly connected with said link and operative by said camming member to effect a disconnection of said link and lever prior to the operation of said finger on said lever.

10. In a typewriting machine, the combination of a vibratory ribbon carrier; an operating lever therefor; an actuating link; an eccentric automatically operative to vary the point of connection between said link and lever; a slide constantly connected with 50 said link; a hand-actuated rock shaft; and a camming member fixed to said rock shaft and operative to actuate said slide.

11. In a typewriting machine, the combination of a vibratory ribbon carrier; an operating lever therefor; an actuating link; an eccentric automatically operative to vary the point of connection between said link and lever; a slide constantly connected with 55 said link; a hand-actuated rock shaft; a camming member or device fixed thereto and

operative on said slide; and a finger also fixed to said rock shaft and operative to shift said operating lever and to maintain it in shifted position.

12. In a typewriting machine, the combination with a ribbon having a plurality of printing fields, of means for automatically vibrating the ribbon so as to bring one of said printing fields opposite the printing point; means operative to maintain the ribbon 75 against vibration during the operation of the machine with another of said fields at the printing point; and means for rendering said ribbon inoperative during the operation of the machine. 80

13. In a typewriting machine, the combination of a vibratory ribbon carrier; actuating means therefor comprising a link and a lever normally connected together; automatic means for varying the point of connection between said link and lever to vary the throw of the ribbon carrier; and means for disconnecting said link from said lever at will, said means comprising a hand-actuated rock shaft, a camming member fixed thereon 90 and a slide operative by said camming member, said slide having a constant connection with said link.

14. In a typewriting machine, the combination with a ribbon divided lengthwise into 95 a wide field and a narrow field having different printing characteristics, of means for automatically vibrating the ribbon to and from the printing point within the limits of the wider ribbon field so as to bring different widthwise portions of said wider ribbon field opposite the printing point, and means operative to maintain the ribbon against vibration during the operation of the machine with the narrower ribbon field at the printing 105 point. 100

15. In a typewriting machine, the combination with a ribbon having a plurality of printing fields normally removed from the printing point, of means including an operating lever for automatically vibrating the ribbon to and from the printing point within the limits of one of said printing fields so as to bring different widthwise portions of said printing field opposite the printing point; and means operative on said operating lever to maintain the ribbon against vibration during the operation of the machine with another of said fields at the printing point. 110

16. In a typewriting machine, the combination with a ribbon having a plurality of printing fields normally removed from the printing point, of means including an operating lever for automatically vibrating the ribbon to and from the printing point within 120 the limits of one of said printing fields so as to bring different widthwise portions of said printing field opposite the printing point; and means operative to lock said operating lever in position to maintain the ribbon 125 130

against vibration during the operation of the machine with another of said fields at the printing point.

17. In a typewriting machine, the combination with a ribbon having a plurality of printing fields, of a vibratory ribbon carrier; actuating means therefor comprising a link and a lever normally connected together; automatic means for varying the point of connection between said link and lever to vary the throw of the ribbon carrier and to use the ribbon widthwise in one of said fields; means for disconnecting said link and said lever at will; and means for setting said ribbon carrier and said operating lever in position to maintain another of said fields of the ribbon opposite the printing point.

18. In a typewriting machine, the combination with a ribbon having a plurality of printing fields, of means for automatically vibrating the ribbon so as to move a different widthwise portion of one of the printing fields to and from the printing point at printing operation; hand-actuated means operative to render said vibrating means inoperative at will and thereby to maintain the ribbon below the printing point in normal position; and hand-actuated means operative at will to position the ribbon with another of its printing fields at the printing point.

19. In a typewriting machine, the combination with a ribbon having a plurality of printing fields, of a ribbon carrier; finger keys; connections between said finger keys and said ribbon carrier, which connections are operative to move the ribbon carrier when the finger keys are actuated, so as to bring different widthwise portions of one of said ribbon fields into use; means for displacing one portion of said connections relatively to another so that actuation of the finger keys will be inoperative to transmit motion to the ribbon carrier and so that the latter will remain quiescent in normal position; and means operative to set said ribbon carrier to bring another printing field of said ribbon into use.

20. In a typewriting machine, the combination with a ribbon having a plurality of printing fields, of a vibratory ribbon carrier; actuating means therefor comprising a link and a lever normally connected together; automatic means for varying the point of connection between said link and lever to vary the throw of the ribbon carrier; means for disconnecting said link and said lever at will so as to maintain the ribbon in normal position during the operation of the machine; and means for moving said ribbon carrier at will so as to bring another of said ribbon fields opposite the printing point.

21. In a typewriting machine, the combination with a ribbon having a plurality of printing fields, of a vibratory ribbon carrier; actuating means therefor comprising a link

and a lever normally connected together; automatic means for varying the point of connection between said link and lever to vary the throw of the ribbon carrier and use the ribbon widthwise in one of said fields; means for disconnecting said link and said lever at will, said means comprising a slideable hand-controlled member and a cam operative thereon; and means for moving said ribbon carrier at will so as to bring another of said ribbon fields opposite the printing point.

22. In a typewriting machine, the combination with a ribbon having a plurality of printing fields and normally removed from the printing point, of types; key-controlled actuating means therefor; means for automatically vibrating the ribbon to and from the printing point within the limits of one of said printing fields; means for maintaining the ribbon quiescent during printing operations so that the types will strike at one side of and without the last mentioned printing field; and means for maintaining the ribbon quiescent so that the types will strike at the opposite side of and without said last mentioned printing field.

23. In a typewriting machine, the combination with a ribbon having a plurality of printing fields and normally removed from the printing point, of types; key-controlled actuating means therefor; means for automatically vibrating the ribbon to and from the printing point within the limits of one of said printing fields so as to bring different widthwise portions of said printing field opposite the printing point; means for maintaining the ribbon quiescent so that the types will strike at one side of and without the variably used printing field; and means for maintaining said ribbon quiescent so that the types will strike at the opposite side of and without the variably used printing field.

24. In a front-strike typewriting machine, the combination of types; key controlled means for actuating said types; a ribbon vibrator; means for automatically moving said vibrator up and down to bring one of said printing fields opposite the printing point; means for maintaining said vibrator quiescent so that the types will strike above the last mentioned printing field; and means for maintaining said vibrator quiescent so that the types will strike below said last mentioned printing field.

25. In a front-strike typewriting machine, the combination with a ribbon having a plurality of printing fields, of a ribbon vibrator; means for automatically moving said vibrator to and from the printing point within the limits of one of said printing fields so as to bring different widthwise portions of said printing field opposite the printing point; means for maintaining the vibrator quiescent in the normal position during the operation of the machine; and means for maintain-

ing the vibrator quiescent in abnormal position during the operation of the machine.

26. In a typewriting machine, the combination of a ribbon having a broad printing field and a narrow printing field differing in character, a ribbon vibrator, an operating lever therefor, a crosswise feeding mechanism for the broad ribbon field normally connected to said lever, and hand actuated means for 5 disengaging the crosswise feeding mechanism from said lever and for operating on said lever to fix the narrow field of the ribbon temporarily in register with the printing point.
- 15 27. In a typewriting machine, the combination of a ribbon having a broad printing field and a narrow printing field differing in character, a vibratory ribbon carrier, an op-

erating lever therefor, actuating means operative on said lever to present different 20 widthwise portions of the broad printing field at the printing point during printing operations, and hand actuated means for disconnecting said actuating means from said lever and for fixing said carrier in position to 25 bring the narrow ribbon field in register with the printing point.

Signed at the borough of Manhattan, city of New York, in the county of New York, and State of New York, this 20th day of 30 November A. D. 1906.

JACOB FELBEL.
